UNITED STATES PATENT OFFICE.

JEAN B. DAUDELIN, OF FALL RIVER, MASSACHUSETTS.

THREAD GUIDE FOR SHUTTLES AND THE LIKE.

Application filed October 12, 1926. Serial No. 142,235

This invention relates to tension devices and in the selected embodiment to tensions for shuttles and as such involves certain improvements over my prior shuttle of my earlier Letters Patent No. 1,508,507, dated September 16, 1924.

In such a shuttle the problem is to maintain a uniform tension in the weft as it is drawn from the weft carrier to the shuttle eye and at the same time properly to guide the weft into the eye in threading and out of the eye after the shuttle is threaded. I secure these results in my present invention through the use of a device which is at once extremely simple and highly efficient. According to it, I provide a weft guide which itself is constructed and arranged to impart a tension to the weft as the weft passes through it from the weft carrier to the shuttle eye. As contemplated herein, such device consists of a helical guide positioned vertically in substantially the longitudinal axis of the shuttle between the weft carrier and shuttle eye and having a tension portion or bar extending forwardly and anchored in the wood of the shuttle throat beyond the threading slot of the shuttle, so that as the weft unspools it wraps itself in one or more turns about this forwardly extending tension bar while working its way towards the center of the helix.

Heretofore experiments have been made with a spirally wound wire in an effort to produce a satisfactory weft tension guide but this did not prove practical in use due to the fact that the thread looped around the wire and broke. In my present invention I secure the advantages sought in the spirally wound wire construction. My construction is entirely practical and has been submitted to long test.

The construction and operation of my invention, together with a suitable illustrative embodiment thereof, is described and shown in the accompanying specification and drawings, and the particular features of novelty are pointed out in the appended claims. In the drawings:—

Fig. 1 is a plan view at the threading end 50 of a loom shuttle of standard type equipped in accordance with my present invention.

Fig. 2 is a section on the line 2—2, of Fig. 1.

Fig. 3 is a side elevation of the combination weft tensioning and guiding device, re- 55 moved.

Fig. 4 is an end view thereof, and Figs. 5 and 6 are detail views of the eye-piece, removed.

I have indicated generally at 1 the threading end of a shuttle of conventional type, at 2 the shuttle throat, at 3 the weft carrier, at 4 the shuttle eye, and at 5 and 6 the usual threading slot connecting the shuttle throat with the outer end of the shuttle eye.

My combination tensioning device and 65 weft guide consists of a helix 7 of flat metal in the form of a plurality of helically wound spaced turns. This helix is positioned vertically in the longitudinal axis of the shuttle between the weft carrier and the shuttle eye 70 and the turns of the helix are preferably disposed in a direction opposite to the unspooling action of the weft, so that as the weft unwinds from the weft carrier it automatically tends to find its way towards the center of the 75 helix where it is held against improper escape. The helix itself may be mounted in any suitable manner in the bobbin chamber of the shuttle, and the opposite side walls of the 80 chamber adjacent the outermost turn of the helix may be lined as indicated at 8 with any suitable cushioning material, as felt, fur or the like.

Extending longitudinally from the center of the helix towards the forward end of the 85 shuttle is a weft tensioning bar 9 which is preferably bent upon itself at substantially right angles, as indicated at 10, to provide an anchoring pin adapted to be driven into the wood of the shuttle slightly in advance of 90 the curved threading slot 5 and clinched within the shuttle, as indicated at 11, in Fig. 2, whereby to anchor the helix in position.

The eye piece 12 consists of a porcelain or other member formed to key within the 95 shuttle eye whereby rotation of the eye piece in the eye is prevented. For this purpose, the eye piece is provided with a longitudinally extended key 13 and 13¹ which is interrupted between its ends by a threading port 14. This 100 key fits within a transverse keyway formed in the shuttle body by counterboring the eye 4, and prevents rotation of the eye piece within the eye.

The weft W from the weft carrier passes 105 through the port 14 and in the threading action of the shuttle is drawn around that part of the key indicated at 13¹ as a snubbing post and laterally outwardly along the eye piece through a threading slot 15, which is 110

channeled in the material of the eye piece itself.

In the threading action of the shuttle, the weft is initially laid between the free or outermost turn of the helix indicated at 7¹, Fig. 4 (located at the left side of the shuttle in Fig. 1), passing beneath the tensioning bar 9 and into the curved part 5 of the threaded slot. As the weft is driven down into said slot and along the horizontally extending portion 6 thereof, and into the eye piece, it gradually works its way inwardly towards the center of the helix, wrapping itself in one or more turns about the tensioning bar 9. In this action, the weft will wrap or twist itself around the tensioning bar 9 in as many turns as there are turns in the helical coil 7.

This not only insures a proper tensioning of the weft, but also guides the weft properly to the eye piece and prevents improper escape of the weft during the run of the shuttle. The width of the metal on the coil may be varied according to the conditions of use. The flat construction of my coil prevents the thread looping around the guide and breaking.

Various modifications in the construction of my device may obviously be resorted to all without departing from the spirit of my invention.

Furthermore such devices as I have described may be used elsewhere than in shuttles, as for example, on winders on other machines where thread tension is required and while I have referred to my invention with particular reference to shuttles and have so shown it for the purposes of illustration, it will be understood that the invention is capable of more extended application and that the shuttle form herein shown and described is intended to be generally illustrative while showing an embodiment of practical utility.

What I therefore claim and desire to secure by Letters Patent is:

1. In a shuttle having a weft carrier and a delivery eye, a thread guide disposed between said weft carrier and eye and consisting of a plurality of spaced, flat turns disposed in broadside relation to each other and wound in a direction opposite to the unspooling action of the weft delivering from said weft carrier whereby the weft in unspooling will automatically work itself towards the center of the guide, said guide having a tensioning element around which the weft wraps itself as it enters said guide.

2. In a shuttle having a weft carrier and a delivery eye, a thread guide disposed between said weft carrier and eye and consisting of a plurality of spaced, flat turns disposed in broadside relation to each other and wound in a direction opposite to the unspooling action of the weft delivering from said

weft carrier whereby the weft in unspooling will automatically work itself towards the center of the guide, one end of said guide extended to provide a tensioning bar around which the weft wraps itself as it enters said guide.

3. In a shuttle having a weft carrier and a delivery eye, a thread guide disposed between said weft carrier and eye and consisting of a plurality of spaced, flat turns disposed in broadside relation to each other and wound in a direction opposite to the unspooling action of the weft delivering from said weft carrier whereby the weft in unspooling will automatically work itself towards the center of the guide, one end of said guide extended to provide a tensioning bar around which the weft wraps itself in a plurality of turns equal to the number of convolutions of the guide as it enters the guide.

4. In an automatically threading shuttle having a weft carrier, an eye, and a threadder located between said weft carrier and eye, a guide carried by said threadder and consisting of a plurality of spaced flat turns disposed in broadside relation to each other and laid in a direction opposite to the unspooling action of the weft whereby the weft will automatically work itself inwardly towards the center of the guide as it runs from the weft carrier, one end of said guide extended to provide a tensioning bar around which the weft wraps itself.

5. A thread guide and tension device for thread delivery with a wound body of thread consisting of a plurality of spaced, flat turns disposed in broadside relation to each other and wound in a direction opposite to the thread wind, said guide having a tension element disposed to receive the wrap of the thread as guided in said helix.

6. A thread guide and tension device for thread delivery with a wound body of thread consisting of a plurality of spaced, flat, turns disposed in broadside relation to each other and of predetermined width wound in a direction opposite to the unspooling action of the thread, said guide having a tension element disposed to receive the wrap of the thread as guided in said helix.

7. A thread guide and tension device for a wound body of thread consisting of a helix having a plurality of spaced, flat, turns disposed in broadside relation to each other and wound in a direction opposite to the unspooling action of the thread, said guide having a tension element disposed in the axis of the helix and about which as a generative center the turns of the helix are substantially described.

In testimony whereof I affix my signature.

JEAN B. DAUDELIN.
